UNITED STATES PATENT OFFICE.

EDWARD E. J. DUQUETTE, OF CENTRAL FALLS, RHODE ISLAND, ASSIGNOR TO HENRY F. BLISS, OF SEEKONK, MASSACHUSETTS.

DESIGN FOR AN AUTOMOBILE KEY.

Application filed November 7, 1923. Serial No. 7,709. Term of patent 8½ years.

To all whom it may concern:

Be it known that I, EDWARD E. J. DUQUETTE, a citizen of the United States, residing at Central Falls, in the county of Providence and State of Rhode Island, have invented a certain new, original, and ornamental Design for an Automobile Key, of which the following is a specification, reference being had to the accompanying drawings, forming part thereof.

Figure 1 is a front elevation of an automobile key embodying my design, and Figure 2, a rear elevation of the same.

I claim:

The ornamental design for an automobile key, as shown.

EDWARD E. J. DUQUETTE.
